UNITED STATES PATENT OFFICE.

JOHN CHARLES McCausland, of PITTSBURG, PENNSYLVANIA.

BOSH-PLATE FOR BLAST-FURNACES.

SPECIFICATION forming part of Letters Patent No. 717,248, dated December 30, 1902.

Application filed May 2, 1902. Serial No. 105,614. (No model.)

To all whom it may concern:

Be it known that I, JOHN CHARLES McCausland, a citizen of the United States, residing at Pittsburg, in the county of Allegheny and State of Pennsylvania, have invented a certain new and useful Improvement in Bosh-Plates for Blast-Furnaces, of which the following is a full, clear, and exact description.

My invention relates to improvements in that class of devices employed for cooling the walls of blast-furnaces which are known in the art as "bosh-plates." Devices of this kind are embedded in the wall of a blast-furnace and make provision for the circulation of water therethrough as a cooling medium. It is well known that the inner or "nose" end of the bosh-plate is more exposed to the heat or to a higher heat than the outer part of the plate, which lies at or near the exposed surface of the furnace, and, furthermore, that one of the problems in devices of this character has been to devise an internal construction which not only secures a natural circulation of the water, but also attains a uniform internal diffusion of the inflowing cold water and at the same time overcomes the lodgment or accumulation of sediment.

The object of the present invention is the production of a simple device which serves to secure a good circulation of water around the nose or inner end of the plate and the uniform diffusion of the water over the upper and lower surfaces of the plate to the end that the plate cannot become cracked or broken, nor can sediment accumulate therein.

To the accomplishment of these ends the invention consists of a bosh-plate embodying certain novel features of construction and arrangement of parts, which will be hereinafter fully described and claimed.

Reference is to be had to the accompanying drawings, forming a part of this specification, in which similar characters of reference indicate corresponding parts in all the figures.

Figure 1 is a plan view, partly broken away and in section, of a bosh-plate embodying my invention, the plane of the section being indicated by the irregular line 1 1 of Fig. 2 looking in the direction of the arrow. Fig. 2 is an elevation looking at the outer or exposed end of the bosh-plate; and Fig. 3 is a

section taken in the plane of the dotted line 3 3 of Fig. 2, also looking in the direction of the arrow.

55

The bosh-plate A is made by casting it in a single piece of metal, either copper or bronze being preferred; but it will be understood that any suitable material may be employed in the manufacture of the article. As 60 is usual in the art, the bosh-plate is chambered to provide for the circulation of a cooling medium therethrough, and said bosh-plate consists of a bottom a, a top b, an outer end wall c, and an inner end wall or nose d. 65 The outer end wall c is curved in an arc whose radius corresponds to the exterior surface of the blast-furnace; but the inner end wall d is not only curved concentric with the wall c, but it is also rounded or curved in 70 cross-section, so as to join the bottom a and top b in the manner shown by Fig. 3. The side walls e converge from the outer end wall toward the inner end wall; but it will be understood that I do not desire to strictly confine myself to the particular form or shape 75 of the bosh-plate as herein disclosed. The corners f at the inner part of the bosh-plate are preferably rounded.

The described construction of the bosh-plate provides an internal circulating-chamber; but in order to secure an equitable distribution of the circulating medium through this chambered plate I prefer to employ a division-wall or partition B, the same being 80 cast as an integral part of the plate, although it may be inserted and secured therein. This partition or division-wall B is disposed in a position parallel to one of the walls of the bosh-plate, preferably to the bottom a, and 85 said partition extends from one side wall e to the other and from the outer end wall c toward the inner end wall d. The partition thus extends the full length of the bosh-plate and joins with the side walls e thereof; but 90 said partition does not extend the full width of the bosh-plate, because its inner edge terminates short of the rounded inner wall d, as shown more clearly by Figs. 1 and 3. The arrangement of the division-plate or partition parallel with the bottom a of the bosh-plate serves to divide the interior of the bosh-plate into upper and lower compartments C 95 C', respectively, and these compartments

2
have communication with each other only along the line of the inner edge of the division-plate B, the latter forming with the end wall *d* the throat *g*. It will be understood that this throat lies at the nose of the bosh-plate and connects the upper and lower compartments of the chamber therein, so as to insure circulation of the cooling medium around the partition B and through the nose *g* of the bosh-plate, which is the hottest part thereof.

The outer end wall *c* of the bosh-plate is provided with a threaded opening or nipple *h*, which has communication with the chamber C and is located at a point at or near the middle of the bosh-plate, said opening or nipple adapted to receive the inlet-pipe, whereby the cold feed-water is supplied to one chamber of the bosh-plate. This wall *c* of the bosh-plate is also provided with another opening or nipple *i*, the latter being in communication with the chamber C and situated, preferably, near the middle of the bosh-plate and close to the plane of the opening or nipple *h*, although the relative positions of the inlet and outlet openings or nipples *h* *i* may be varied within the skill of the constructor. The opening or nipple *i* is adapted to receive or have coupled thereto an off-bearing or outlet pipe, which serves to convey the hot water away from the bosh-plate, and it will be noted that the off-bearing or discharge pipe has communication with the compartment C' of the bosh-plate, thus disposing the connection of the inlet and outlet pipes on opposite sides of the partition or division-plate B and insuring the supply of cold water to one chamber and the exit of the heated water from the other chamber of the bosh-plate.

D indicates a deflector which is disposed in the compartment C of the bosh-plate at a point opposite to the inlet opening or nipple *h*. This deflector may be secured in the chamber of the bosh-plate, or it may be cast as an integral part thereof, and said deflector may take any appropriate form, so as to diffuse the inflowing current of water over the bottom *a* of the bosh-plate. As shown by Fig. 1, however, a suitable form of the deflector is the acute-angled form having its apex facing toward the inlet opening or nipple, while the inclined surfaces of this deflector diverge rearwardly and toward the corners *f* of the bosh-plate. The inflowing water impinges on the apex of the deflector, and the diverging surfaces thereof diffuse the water over the bottom *a* and through the lower chamber C, thereby directing the water toward the corners and the inner end or nose of the bosh-plate.

One of the peculiarities of my invention

resides in the top *b* of the bosh-plate having an upwardly-arched form, as shown more clearly by Fig. 2, said arched top gradually sloping in a downward and inward direction 65 toward the inner wall or nose of the bosh-plate, thus making the bosh-plate narrower at the nose than at the outer end. This particular form of the top *b* has a tendency to equalize the flow of the water over the partition or plate B, and this equalization of the circulation will tend to keep the whole inner part or nose of the bosh-plate at an even temperature.

Having thus described my invention, I 75 claim as new and desire to secure by Letters Patent—

1. A bosh-plate provided with a continuous horizontal chamber which extends from front to rear and from side to side thereof, a horizontal division-plate extending through said chamber from the rear nearly to the front and dividing the chamber into upper and lower compartments which communicate only at the inner end of the bosh-plate, and water connections located at the outer edge of the bosh-plate and on opposite sides of the line of union between the division-plate and the outer end wall of the bosh-plate.

2. A bosh-plate comprising side and end walls, a top and a bottom, the whole forming a chamber which extends continuously from rear to front and from side to side, a horizontal division-plate extending through said chamber from the rear nearly to the front and dividing the chamber into upper and lower compartments which communicate uninterrupted at the front of the plate, the top of said bosh-plate being arched transversely and inclined toward the division-plate, such inclination of the top being in a downward direction from the rear toward the front and making the upper compartment of the chamber increase in depth from the front toward the rear.

3. A bosh-plate provided with a division-plate disposed substantially parallel to the bottom thereof and having compartments which communicate only at the inner portion or nose of said bosh-plate, inlet and outlet openings in communication with the respective compartments of said bosh-plate, and a deflector disposed in one compartment in a position opposite to the inlet-opening.

In testimony whereof I have signed my 115 name to this specification in the presence of two subscribing witnesses.

JOHN CHARLES McCausland.
